UNITED STATES PATENT OFFICE.

HANS ZIMMERMANN, OF PHILADELPHIA, PENNSYLVANIA, ASSIGNOR TO SCHUTTE & KOERTING COMPANY, OF PHILADELPHIA, PENNSYLVANIA, A CORPORATION OF PENNSYLVANIA.

TUBULAR HEAT-EXCHANGING APPARATUS.

1,168,368.

Specification of Letters Patent. Patented Jan. 18, 1916.

Application filed November 12, 1914. Serial No. 871,667.

To all whom it may concern:

Be it known that I, HANS ZIMMERMANN, a subject of the German Empire, residing in the city and county of Philadelphia, in the 5 State of Pennsylvania, have invented certain new and useful Improvements in Tubular Heat-Exchanging Apparatus, of which the following is a true and exact description, reference being had to the accompanying drawings, which form a part thereof.

My present invention relates to tubular heat exchanging apparatus of what may be called the surface condenser type, and has for its object to provide the improvements 15 hereinafter explained in the construction of a tubular element for use in such apparatus and in which the group of open or active tubes are rigidly connected at their ends into the tube sheets or partitions.

20 The various features of novelty which characterize my invention are pointed out with particularity in the claims annexed to and forming a part of this specification. For a better understanding of my invention 25 however, and the advantages possessed by it, reference should be had to the accompanying drawings and descriptive matter in which I have illustrated and described the apparatus embodying a preferred form 30 of my invention.

Of the drawings: Figure 1 is a sectional elevation of an assembled tubular heat exchanging device. Fig. 2 is a section on the line 2—2 of Fig. 1. Fig. 3 is an elevation 35 partly broken away and partly in section showing one of the baffle spacing devices and portions of the tube sheets and baffles engaged thereby. Fig. 4 is a sectional elevation through the central dead tube and 40 adjacent portions of the tube sheets and baffles.

The heat interchanging device shown in the drawings comprises a tubular casing A formed with inlet and outlet ports A¹ and A², respectively, adjacent its ends, and with inlet and outlet ports A³ and A⁴, respectively, somewhat more remote from its ends. Within the casing are located a group of active tubes B which are rigidly connected 50 at their ends to tube sheets or partitions C and C¹. The latter serve as partitions to divide the interior of the casing A into two end chambers a¹ and a² connected by the tubes B and a central chamber traversed by the 55 tubes. The fluid passing through the tubes

B first enters the chamber a¹ of the casing A, through the inlet port A¹ and passes out of the casing A through the chamber a² and the outlet port A². The fluid passing through the inter tube space between the 60 tube sheets C and C¹ enters the central chamber of the casing A through the inlet port A³ and leaves through the outlet port A⁴. As shown, the tube sheet C is anchored to the casing A, but the tube sheet C¹ is 65 permitted axial movement relative to casing A to accommodate the thermal expansion of the tubes B relative to the casing.

The provisions, collectively indicated by the symbol M, for preventing leakage between chamber a² and the central chamber through the joint between need not be described in detail herein as these provisions are disclosed in detail and claimed in my co-pending application, Serial No. 855,114. 70 The device shown in the drawings while adapted for many uses, is specially devised for use as an oil cooler, the oil entering the apparatus through the port A¹ and leaving through the port A², while water for cooling the oil is admitted to the central chamber of the device through the port A³ and is discharged through the port A⁴. 75

To cause the fluid entering and leaving the central chamber of the apparatus 85 through the ports A³ and A⁴ respectively, to flow back and forth transversely of, as well as longitudinally of the tubes B, I employ alternately disposed baffles E and F. The baffles E are in the form of annuli or 90 disks formed each with a large central aperture and each extending at its periphery into contact with the casing A which, as shown, is formed with internal ribs A⁵, the inner curved walls of which are engaged by the 95 peripheral edges of the disks E. The alternate baffles F are in the form of disks separated at their peripheral edges from the casing so that the fluid going through the casing between the ports A³ and A⁴ takes 100 the zigzag course in toward, and out from the center of the casing indicated by the arrows. The baffles E and F are formed with apertures snugly receiving the corresponding tubes B. To insure the proper 105 spacing of the baffles therefore, a set of baffle spacing devices are employed. As shown, there are three baffle spacing devices each of which comprises a tube G which may advantageously be of the same diameter 110

as the tubes B and which passes through apertures in the baffles E and F, tubular spacing members H strung on the tube G and each spacing an adjacent pair of baffles E and F apart, and tubular spacers H¹ surrounding the tube G and extending between the tube sheets C and C¹ and the adjacent baffles. As shown, each tube G which is rigidly connected at its ends to the tube sheets C and C¹, is closed at its ends by plugs I so that there is no circulation therein of the fluid passing through the tubes B. Each tube G will, in consequence, have a thermal contraction and expansion different from that of the tubes B, and to accommodate the tendency to a relative expansion and contraction in length of the tube G relative to the tubes B, I form a series of transverse cuts or slots, G¹ in the tube G adjacent each end. This permits of a sufficient contraction and expansion of the tube G relative to the tubes B without subjecting the connections of any of the tubes to the tube sheet C to an undesirable strain. Similarly I form cuts H² in one or more of the tubular spacing sections surrounding each tube G. As shown, these cuts are formed in each of the end pieces H¹.

The sealing of the ends of the tube G and of the tube sheet ends of the tube sections H¹ is obviously necessary to prevent leakage with the cuts G¹ and H² formed in the walls as described. Even though there were as free a circulation between the chambers a¹ and a² through the tubes G, as through the tubes B, there would be a tendency to a relative expansion and contraction in length of the tubes G relative to the tubes B, owing to the fact that the temperature attained by the tubes G would be different from the temperature attained by the tubes B on account of the heat insulating effect of the sections H and H¹ which of course, would also tend to contract and expand relative to the tubes G.

As shown, the ends of the tubes G are filled by the reduced inner ends of plugs I. The outer ends of the plugs I, while larger in diameter than the internal diameter of the tubes G, are, as shown, smaller in diameter than the internal diameter of the tube sections H¹, by which they are surrounded. The joints between the outer ends of the plugs I and tube sections H¹ are brazed as indicated at J and by the metal out of which the corresponding tube sheets C and C¹ are formed, if as may well be the case, these tube sheets are formed by metal cast about the ends of the tubes.

With my improved baffle spacing construction described, it will be apparent that the baffles may be accurately spaced as desired and this is a matter of substantial practical importance especially in the case of apparatus designed for operation at high

capacity and with high efficiency. Furthermore, the baffles are spaced in a relatively inexpensive manner and by means pertaining exclusively to the tubular element as distinguished from the surrounding casing 70 of the apparatus.

My novel expedient of making a closed or inactive tube readily variable in length to compensate for the tendency toward relative expansion and contraction in length between 75 it and open active tubes which like the inactive tube, are anchored at their ends in the tube sheets of apparatus of the kind under consideration, may be employed in connection with other inactive tubes than those 80 forming a part of the baffle spacing means. For instance, this expedient may be employed, as shown in the drawings, in the case of the inactive central tube K having the transverse cuts K¹, has its ends closed 85 by plugs L, shaped to serve as centering pieces by which the tubular element, as a whole, may be mounted in a lathe to enable the peripheral edges of the tube sheets C and C¹ and the peripheral edges of the baffles F, 90 if necessary, to be turned. It is not practically feasible to remove these centering pieces after the tubular element is machined. The tube K forms a convenient means for initially holding the centering pieces in position, while the tube sheets C and C¹ are cast in place, and also serves as a displacing member to fill the otherwise existing and objectionable dead space in the center of the tubular element. 100

While in accordance with the provisions of the statutes I have illustrated and described the best form of my invention, now known to me, those skilled in the art understand that changes may be made in the 105 form of the apparatus disclosed herein without departing from the spirit of the invention covered by the claims and that under certain conditions, certain features of my invention may be used without the corresponding use of other features. 110

Having now described my invention, what I claim as new and desire to secure by Letters Patent, is:

1. In tubular heat interchanging apparatus, a tubular element comprising a set of open tubes and tube sheets to which the ends of said tubes are rigidly connected, and one or more closed tubes, each rigidly connected at its ends to said tube sheets and made 120 readily expansible and contractile in length to compensate for the difference in the thermal expansion and contraction of the closed tubes relative to the open tubes.

2. The combination in a tubular heat interchanging element comprising open tubes and tube sheets to which the ends of the tubes are rigidly connected and which are free to approach and separate from one another as said tubes contract and expand; and 130

one or more closed tubes each extending between and rigidly connected at its ends to said tube sheets and formed with transverse cuts to render it readily expansible and contractile in length.

3. In tubular heat interchanging apparatus, a combination with a set of open tubes and tube sheets to which the ends of said tubes are rigidly connected, of baffles extending transversely to said tubes through the inter tube space, and baffle spacing means comprising one or more closed tubes, each rigidly connected at its ends to said tube sheets, and made expansible in length in comparison with said open tubes.

4. In tubular heat interchanging apparatus, a combination with a set of open tubes and tube sheets to which the ends of said tubes are rigidly connected, of baffles extending transversely to said tubes through the inter tube space, and baffle spacing means comprising one or more closed tubes, each rigidly connected at its ends to said tube sheets, and made expansible in length in comparison with said open tubes passing through apertures in said baffles and a set of

tubular spacing sections proper surrounding said closed tube, and interposed between adjacent baffles and between the tube sheets and adjacent baffles.

30

5. In tubular heat interchanging apparatus, a combination with a set of open tubes and tube sheets to which the ends of said tubes are rigidly connected, of baffles extending transversely to said tubes through the inter tube space, and baffle spacing means comprising one or more closed tubes, each rigidly connected at its ends to said tube sheets, and made expansible in length in comparison with said open tubes passing through apertures in said baffles, and a set of tubular spacing sections proper surrounding said closed tube, and interposed between adjacent baffles and between the tube sheets and adjacent baffles, one or more of said spacing sections being made readily expansible and contractile in length.

HANS ZIMMERMANN.
